UNITED STATES PATENT OFFICE.

ANDREW A. ABBOT, OF BOSTON, MASSACHUSETTS.

PORTABLE FIRE-ESCAPE.

1,160,809.

Specification of Letters Patent.

Patented Nov. 16, 1915.

Application filed August 20, 1914, Serial No. 857,734. Renewed July 30, 1915. Serial No. 42,827.

To all whom it may concern:

Be it known that I, ANDREW A. ABBOT, a citizen of the United States, residing at Boston, in the county of Suffolk and State 5 of Massachusetts, have invented certain new and useful Improvements in Portable Fire-Escapes, of which the following is a specification.

My invention relates to new and useful 10 improvements in fire escapes of the portable type and has for its primary object to provide an extremely effective device comprising a vehicle having a frame structure thereon to be raised along side of a building and 15 inclined forwardly so that the occupants of the building may by getting into the car carried upon the top of the structure be lowered in a safe and expeditious manner to the ground.

20 An important object of my invention is to provide a fire escape of the character described that is mounted upon a vehicle so as to be readily moved from place to place, said fire escape being mounted upon a body 25 that is pivoted centrally to the vehicle body and arranged to be moved at right angles to the vehicle body so as to prevent tilting and provide a more stable support for the escape.

30 Another important object of my invention is to provide a fire escape consisting of a lazy-tong structure that is to be elevated and inclined and is provided with a car to accommodate the persons to be rescued, said 35 car being mounted upon the top of the structure and so arranged as to assume an approximately horizontal position at all times to insure a safe descent.

Another object of importance is to provide 40 novel means for elevating the lazy-tong structure, tilting and lowering it, that is operable from a vehicle or base of the fire escape, is simple as to construction and easy to operate.

45 Another important object is to provide means to limit the elevating and tilting action of the lazy-tong structure so as to insure stability and a safe descent.

The above and additional objects are 50 accomplished by such means as are illustrated in the accompanying drawings, described in the following specification and then more particularly pointed out as claimed.

With reference to the drawings, wherein 55 I have illustrated the preferred embodiment

of my invention as it is reduced to practice, and throughout the several views of which similar reference numerals designate corresponding parts:

Figure 1 is a side elevation of my improved device as it would appear when in assembled position, Fig. 2 is a top plan view showing the supporting body turned at right angles to the vehicle body and the lazy-tong structure broken away and in section, Fig. 3 is a fragmentary side elevation showing the lazy-tong structure in extended and inclined or tilted position, Fig. 4 is a side elevation showing the lazy-tong structure partly broken away and as it would appear when in upright extended position, Fig. 5 is a side elevation showing the lazy-tong structure broken away and in position as it would appear when inclined or tilted, Fig. 6 is a transverse sectional view showing the 60 construction of the supporting carriage, and Fig. 7 is a detail transverse sectional view showing the detail construction of the clutch mechanism.

Referring to the drawings by characters 65 of reference the numeral 1 designates as an entirety a vehicle comprising a body 2 supported by wheels 3 in the usual manner.

Mounted on the body 2 is a platform 4 that is pivoted centrally to the body and provided at each end with an upstanding supporting plate 5. The platform 4 is designed to be swung or turned similarly to a turn table upon the vehicle to provide for 70 stability of the device as will be later more fully described.

Mounted longitudinally of the platform 4 are two pairs of rods 6 and 7. The pair 6 being arranged in slightly spaced relation to the platform 4 with the ends of each rod secured in the plates 5. Each rod of the pair 6 is disposed adjacent to one longitudinal edge of the platform 4. The upper pair 7 is arranged similarly to the one 6 but in 75 superposed relation thereto.

Mounted upon the platform 4 is a lazy-tong structure designated 8 as an entirety, carrying at its upper extremity a horizontally disposed platform 9 to accommodate the persons to be saved. The lazy-tong 80 structure comprises a plurality of pairs of pivoted bars 10. The bars 10 are pivoted to each other at their ends and in pairs centrally of their ends. One pair of the lowermost bars 10 is pivoted adjacent the ends 105 110

of a transverse bar 11 secured to the rods of the pair 7 at certain ends thereof. The other pair of lowermost bars 10 is pivoted to a transverse rod 12 that is operatively connected with the elevating lowering and tilting mechanism designated 13 as an entirety.

The mechanism for elevating, tilting and lowering the structure 8 consists of two links 14 and 15 that are pivoted at their ends to the transverse bar 12 and to the carriages 16 and 17 slidably mounted upon the rods 6 and 7 respectively. The carriages 16 and 17 each comprise a transverse plate 18 having collars 19 on the ends thereof that slide upon the rods 6 and 7. Mounted one above the other and longitudinally of the platform 4 are rotatable and screw threaded operating shafts 20 and 21 that are extended through screw threaded openings formed in the plate 18 of the carriages 16 and 17 respectively. The shafts 20 and 21 are journaled suitably in one of the plates 5 carried on the platform 4. Gears 22 and 23 are mounted on the shafts 20 and 21. The gear 22 is keyed upon the outer end of the shaft 20, said shaft 20 being extended through the plate 5 in which it is journaled sufficiently to enable the mounting of the gear 22 thereon. The shaft 21 is extended in the same manner for a greater distance than the one 20 and said extended portion is flattened upon its upper face as at 24. The gear 23 is slidable upon the flattened extended portion 24 of the shaft 21. Carried by the gear 23 is a sleeve 25 provided with a flat face 26 to coöperate with the flat face 24 on the extended portion of the shaft 21. It will be readily seen that the gear 22 may be moved into and out of meshing engagement with the gear 23. A crank handle 27 is operatively connected with the extended end of the shaft 21.

To prevent the structure 8 being elevated too far I provide stop pins 28 mounted on the platform 4 and designed to engage the plate 18 of the lower carriage 16 as shown in Fig. 4 in the drawings when the lazy-tong structure 8 is in its upright extended position.

To elevate the structure 8 from the position as shown in Fig. 1, the crank 17 is grasped and turned to rotate the shaft 21. When the shaft 21 rotates the gears 22 and 23 mesh causing rotation of the lower shaft 20 and subsequently the sliding movement of the carriages 16 and 17. As the carriages 16 and 17 slide on the rods 7 the bars 10 comprising the structure 8 are moved from expanded to contracted position that is, toward each other at their lower ends causing the structure to be raised upwardly. The pins 28 in engaging the plate 18 of the lower carriage 16 limit the sliding movement of the carriage and subsequently the upward movement of the structure 8. The mecha-

nism assumes the position as shown in Fig. 4 when the structure 8 is in its upright extended position.

To incline the structure 8 as shown in Figs. 3 and 5 so that the platform 9 will be positioned within or adjacent to the window or side of a building, the gear 23 is moved toward the outer end of the shaft 21, out of meshing engagement with the gear 22 and the shaft 21 rotated. The shaft is rotated in a clockwise direction causing the pair of bars 10 of the structure 8, that are lowermost and toward the front end of the vehicle to be lifted upwardly with relation to the rods 7 on the platform 4. As these bars 80 are lifted upwardly, the structure 8 is inclined rearwardly to the position shown in Figs. 3 and 5 in the drawings.

In order to move the structure into vertical extended position so that it may be lowered to a position shown in Fig. 1 in the drawings, the shaft 21 is rotated in a counter clockwise direction until the lower end of the structure 8, each comprising one of the lowermost pairs of the bars 10 thereof engage the bars 7. At this time the adjustment is limited and the gears are moved into meshing engagement with each other. When the gears mesh with each other the crank handle 27 is then turned to cause the structure 8 to be lowered to position as shown in Fig. 1 in the drawings. It will be readily seen that one person may easily and readily operate the device so that the structure 8 may be raised and tilted as described.

To insure stability of the device and prevent tilting, I provide an extensible U-shaped bar 29 the arms of which are slideable in longitudinal openings formed in the platform 4. The bar 29 is designed to be pulled outwardly from one end of the platform 4 as shown in Fig. 2 in the drawings so that a number of persons may grasp the same to steady the structure when in operative position.

With reference to the foregoing description and accompanying drawings it will be readily seen that I have provided a simple and inexpensive device that will prove of great service to fire departments and enable a safe and expeditious descent of persons from burning buildings. It will be plainly seen that my improved device may be used to elevate a hose so that water may be played upon a burning building, in this instance the firemen taking a place in the platform 4 at the top of the lazy-tong structure 8.

In practice, I have found that the form of my invention, illustrated in the drawings and referred to in the above description, as the preferred embodiment, is the most efficient and practical; yet realizing that the conditions concurrent with the adoption of my device will necessarily vary, I desire to

emphasize the fact that various minor changes in details of construction, proportion and arrangement of parts may be resorted to, when required, without sacrificing any of the advantages of my invention as set forth.

What is claimed is:—

1. A fire escape comprising a support, a lazy-tong structure mounted on said support and designed to be elevated in a vertical plane and then tilted forwardly, longitudinal rods mounted on said support, carriages 10 slidable upon said rods, said lazy-tong structure comprising a plurality of pivoted bars arranged in pairs, the bars of one of the lowermost pairs being pivoted to said support, links connecting the lower ends of the bars of the other lowermost pair with the carriages, screw threaded shafts operatively 15 connected with the carriages and rotatably journaled in the support, gear wheels mounted on the shafts and meshing with each other, and one of said gear wheels being slidable and to be moved out of meshing 20 engagement with the other gear wheel.

2. A fire escape comprising a support, a plurality of rods arranged horizontally and longitudinally of the support, parallel and in spaced relation to each other in pairs, carriages 30 slidable on the rods, screw threaded shafts rotatably journaled in the support and extending through the carriages to facilitate the sliding thereof upon the rotation of the shafts, a stationary transverse 35 bar arranged at one end of the support, a lazy-tong structure comprising a plurality of pairs of pivoted bars, the lower ends of one of the lowermost pairs of bars being pivotally connected with said transverse bar, the lower ends of the other bars of the 40 lowermost pair of the lazy-tong structure being operatively connected with the carriages, a transverse bar connecting the lower ends of said last named pair, pairs of links pivoted 45 at their ends to the carriages and said trans-

verse bar last named, gear wheels mounted on said rotatable shaft, one of said gear wheels being arranged to move out of meshing engagement with the other whereby the structure may be inclined forwardly after 50 being elevated.

3. A fire escape comprising a support, a platform pivoted on the support, a lazy-tong structure operatively connected with the platform, a U-shaped bar slidable within the 55 platform at one end thereof, and means to elevate and tilt the lazy-tong structure.

4. In a fire escape the combination with a support of a lazy-tong structure mounted on said support, a plurality of horizontally disposed rods extending longitudinally of the support, carriages slidable on the rods, links 60 pivotally connected with the carriages and certain lower extremities of the lazy-tong structure, the other lower extremities of the 65 lazy-tong structure being pivoted at a fixed point on said support, and means interchangeably operable through moving both links to extend the lazy tongs and operable to fix one link and move the other to tilt the 70 lazy tongs.

5. In a fire escape, a support, a lazy tong structure mounted on said support, carriages 75 slidably carried by the support, links pivotally connected with the carriages and certain lower extremities of the lazy-tong structure, the other lower extremities of the lazy-tong structure being pivoted at a fixed point on said support, a platform carried by said lazy-tong structure and to be elevated thereby, and means interchangeably operable through moving both links to extend the 80 lazy-tongs and operable to fix one link and move the other to tilt the lazy-tongs.

In testimony whereof I affix my signature 85 in presence of two witnesses.

ANDREW A. ABBOT.
